SHIPPING CONTAINER

Armin Elmendorf, Winnetka, Ill.

Application June 19, 1950, Serial No. 168,956

7 Claims. (Cl. 217—17)

The invention relates to an improvement in containers, and, particularly, in shipping containers. One purpose is to provide a shipping container in which a veneer material, known by the trade name of "Ply-Veneer," is employed, such veneer being an invention and development of the present applicant.

Another purpose is to provide a shipping container which may be shipped flat, and is easily assembled.

Another purpose is to provide a shipping container in which the sides are adequately reinforced by cleats, and the box sides are made of one piece of box board which can be bent to a right angle at the box edges, with the corners reinforced with steel strapping which cannot buckle up and snag other boxes in shipment.

Another purpose is to provide an improved corner structure for shipping containers.

Another purpose is to provide an improved reinforcing structure for the corners of shipping containers made of "Ply-Veneer" or of other suitable materials.

Other purposes will appear from time to time in the course of the specification and claims.

I illustrate my invention more or less diagrammatically in the accompanying drawings wherein:

Figure 1 is a perspective view of an embodiment of my invention;

Figure 2 is an end elevation of the structure of Figure 1, with parts broken away and with the top shown in open position;

Figure 3 is a section, on an enlarged scale, on the line 3—3 of Figure 1;

Figure 4 is a perspective view illustrating the knocked-down assembly of the structure of Figure 1;

Figure 5 is a section, on an enlarged scale, on the line 5—5 of Figure 4;

Figure 6 is a section, on an enlarged scale, on the line 6—6 of Figure 1;

Figure 7 is a partial plan view of a variant form of construction;

Figure 8 is a section on the line 8—8 of Figure 7;

Figure 9 is a view similar to Figure 8, of another variant form of construction;

Figure 10 is a perspective view of a knocked-down structure of an open-topped container made in accordance with my invention;

Figure 11 is a perspective view of the container of Figure 10; and

Figure 12 is a partial plan view, similar to Figure 7, of another form of my invention, with a different reinforcement.

Like parts are indicated by like symbols throughout the specification and drawings.

Referring to the drawings, it will be understood that the invention may be applied to containers, such as shipping containers, of different sizes, shapes and proportions.

Whereas my invention may be applied to a wide variety of materials or boards, I illustrate it in connection with a composite board in which a layer of veneer is positioned between two adhering layers of relatively strong fiber or paper.

As shown in the various figures, the veneer, which may be distended, is adhesively secured between an inner layer 2 and an outer layer 3 of fiber or paper. The veneer is preferably sufficiently separated along the grain to permit the expansion or contraction of the individual wood elements 1 to be without direct effect on the composite board or layer as a whole. There will thus be

no tendency to buckle when a container in which the board is used is subjected to moisture.

In considering the container of Figures 1 and following, I illustrate it as formed in one piece, which includes four large connected panels A, B, C, D and a closure panel or small flap E, forming a single piece or shell. The five panels may be formed of a single piece or sheet of my composite veneer and paper or fiber material, or of fiber-board or of any other suitable box-board. The knocked-down form, as shown in Figure 4, may be shipped and stored flat. When assembled into the completed container of Figure 1, the five panels are connected by what I may call hinges, there being four of these hinges. Each hinge constitutes and is formed by a bend in the sheet. Referring, for example, to Figure 5, I provide a space or break, as at 4, between the paper or fiber layers 2 and 3, in which the wood or other solid filler is omitted. As a result, the sheet can readily be bent, as shown in Figure 2, to form a right angle in which the outer bend or outer part of the material is in tension, whereas the inner part of the material is in compression, as will later be discussed in greater detail. If conventional fiber-board or the like is used, the usual scored fold or bend may be used.

25 I find it advantageous to provide a supporting frame for the board. This frame may be formed by cleats or reinforcements 5, for example of wood, which are secured to the various panels A, B, C and D. With reference to Figures 2 and 3, I illustrate cleats or boards 5, the opposed ends of which may be formed as mortise and tenon to interpenetrate and to strengthen each other. As will be clear, for example, from Figure 5, the adjacent ends of opposed cleats 5 are spaced apart, when the form or assembly is in the flat, by a break or separation 4, generally smaller than the gap in the veneer in the composite board. The larger gap in the veneer provides space for the folded paper or fiber at the inner surface of the corner.

When the form or assembly is spread out for shipment or storage, as shown in Figure 4, the panels A, B, C, D and E may be substantially or completely flat, with their various cleats 5 spaced apart at the ends, and with their opposed mortise and tenon elements open, but ready for entry. Whereas I have shown the cleats as in mortise and tenon form, it will be understood that any other suitable end formation may be employed. For example, they may be mitered, or they may be square-ended, with space allowed to permit the panels to be bent at a 90-degree angle in relation to each other. However, the mortise and tenon form is advantageous as providing substantial support against transverse strain endwise of the box, or at an angle to the sides of the box.

Whereas I may form the box ends in any suitable way, I find it advantageous to employ end panels F and H, the ends of which extend beneath the cleats 5a of the panel B. The panels F and H may be scored along the edges of the cleats 5a for easy bending, or a hinge structure may be employed, such as is shown in Figures 3 and 6, in connection with an interruption in the "Ply-Veneer" structure.

60 Thus, in order to assemble the structure of Figure 4, to produce the container of Figures 1, 2 and 3, all that is necessary is for the user to bend the panels along their hinges, while causing the mortises and tenons to interpenetrate. The closure may be completed by securing the flap E, as shown in Figure 1, for example by driving in suitable nails or securing members 10 through the flap E and into the cleats of the panels A or D. If additional reinforcement or securing means is desired, a wire or flap strap may be drawn tight around the box. I illustrate, for example, in Figure 1, a strap structure 12. It is provided with a loose end 13 which may be clamped or secured to the other end of the strap, at 14, to complete the closure of the box. To hold the panels to the cleats, I illustrate, for example, any suitable nails or staples 15, the ends of which may be knocked in or recurved, as at 16 in Figure 3. The panels F and H, when the container is assembled as in Figures 1 and 2, may be secured in any suitable manner to the inner surfaces of the adjacent cleats 5 and 5a. This may be done by the use of an adhesive, or by the use of staples, nails, or any other

securing means. The result is a strong structure, ideally adapted to resist strain and wear.

Whereas the above described structure may be employed, under some circumstances, without additional reinforcement, I find it advantageous to employ a metal element or strap at the corners. I illustrate, for example, an element 20 which may be a thin steel strap narrower in width than the cleats. It may be recessed into the surface of the veneer core, and preferably extends around the full perimeter of the box. It may be recessed into the outer surface of the veneer before the outer layer of paper 3 is applied, or it may be pressed into the paper and veneer in the process of applying the paper in a press. When the parts are bent into the corner position, as shown, for example, in Figure 3, one of the steel straps or members 20 is located at each end of the container. The strap 20, upon being flexed, is under tension, but the fiber structure within it, at each corner of the box, is held under substantial compression. Securing means, such as the nails 15, may be driven readily through the thin metal members or steel straps 20, as shown in Figure 3.

In the form of Figures 7 and 8 I illustrate a corresponding strap 21 as applied exteriorly to a layer of kraft paper or fiber 3a, which corresponds to the layer 3 of Figure 3. The metal strap or element 21 may be covered by an additional outer paper or fiber strip or layer 22.

The form of Figure 9 differs from the form of Figure 8 in that the same reinforcing structure is shown as applied to a different box side material. The member 23, for example, may represent fiber-board, to the exterior of which a metal strap 24 is applied. It, in turn, is covered by an outer layer 25 of paper, fiber, or the like. It will be understood that, as to the reinforcing and corner structures of Figures 7 to 9, they will be understood as being applicable to the formation of the container of Figure 1, or the knocked-down form or assembly of Figure 4.

In Figures 10 and 11 I apply my invention to an open-topped box, such as is customarily used for shipping apples and other fruits. Since an upwardly bulged top or cover is ordinarily employed, which does not, of itself, form part of my invention, I do not illustrate it, but merely the open-topped box or container itself. It will be understood that the knocked-down form of Figure 10 may be made of the composite material of Figures 1 to 8, or may be made of any other suitable material, such as the fiber-board indicated in Figure 9. In any event, the form of knocked-down structure includes panels X, Y and Z, each with its appropriate cleats 5x and 5xx. Hinged beneath the cleats 5xx of the panel Y are hinge panels M and N, with their cleats 70, 71. The panels M and N may be hinged like the panels F or H, as shown in some detail in Figure 6, in connection with the form of Figures 1 and following. Whereas the structure can be shipped readily, flat, in knocked-down form, it is very easily assembled. If the panels X, Y and Z are bent at right angles to each other, as shown in Figure 11, the lower corners of the box are formed by the mortise and tenon structure shown at the opposed ends of the cleats, or square ends or mitered ends may be used. The panels M and N are then swung into vertical position. The outer ends of the cleats of panels Z, X are cut back, as at 72, to leave space for the end portions of the cleats 70, 71. The parts may then be nailed or otherwise secured together, and a strong box is provided into which fruit or other materials can be filled. After the container is filled, then any suitable top member, such as the usual slat cover, may be nailed, stapled, or otherwise applied. In hinging the end panels F and H or M and N, I may omit the filler shown, for example, at 100 in Figure 6, under the overlying cleat.

It will be realized that whereas I have described and claimed a practical and operative device, nevertheless many changes may be made in size, shape, number and disposition of parts without departing from the spirit of my invention. I therefore wish my description and drawings to be taken as in a broad sense illustrative or diagrammatic rather than as limiting me to my specific showing herein. It will be understood, for example, that all forms of container herein shown may be made of the composite material shown in Figures 1 and following, but may also be made of fiber-board or other suitable

material. I may provide the closure structure as herein shown, without employing a reinforcing metal corner, but I prefer to employ the peripheral metal reinforcements such as are shown at 20 in Figure 3, 21 in Figures 5 7 and 8, 24 in Figure 9, and 75 in Figure 10. It may be a matter of choice whether the metal reinforcement is received in a recess, as in the form of Figures 1 and following, or is covered by an outside layer of material, as shown in Figures 7, 8 and 9. It will be understood, 10 also, that whereas I illustrate flat metal strips or straps, wires may be employed, or any other suitable metallic reinforcements, as illustrated in Figure 12.

The use and operation of my invention are as follows:

I illustrate two types of container herein, both of which are formed from knocked-down structures in which a plurality of panels are hinged to each other, and may be shipped or stored flat. I find that an advantageous structure consists of a multi-layer sheet in which veneer is confined between inner and outer or upper and lower layers, having the general characteristics of kraft paper, fiber, or the like. A practical way of forming the hinges is to leave a space or gap in the veneer between the paper layers. This corner structure is well shown, for example, in Figure 3. Each panel has cleats or reinforcements 5 or 5a, secured to it, which connect, abut or interpenetrate at the corners to provide a strong reinforcing structure. I further prefer to employ a metal strap, such as a flat steel element, which is bent around the corners at the ends of the box, and which thus provides an outer compression member which maintains the corner structure within it under substantial compression. As will appear, for example, from Figure 3, the steel strap 20 maintains the fiber element 2 in compression. The result is a structure of great strength which will resist shock and strain, but which is light and sightly. It will be understood that the corner structure may be employed with other materials, such as fiber-board. It will also be understood that the structures herein shown may, under some circumstances, be employed without the metal reinforcement, although I prefer its employment. Cord or twine might be used.

Whereas I have shown two specific containers, it will be understood that my structure is applicable to a wide variety of different forms and shapes of containers. I find that the hinged end panels, such as are shown in Figures 4 and 10, are advantageous in providing a container which can be shipped readily as a knocked-down unit, and quickly assembled, with a minimum of time and effort, into a strong and useful container.

I claim:

1. A box including a composite box board shell constituting at least three connecting panels of a box, the box board consisting of a layer of veneer bonded between two layers of strong paper, the shell being divided 55 by hingeable portions into a plurality of stiff wall panels located at right angles to each other, each said wall panel having at its ends cleats at right angles to the grain of the veneer, the cleats being formed and adapted to engage when the panels are bent at right angles to each other, the edges of the adjacent panels being separated by gaps in the veneer having a width not less than the thickness of the veneer, at least one paper layer spanning each such gap, and continuous flexible metal reinforcing straps extending about each end of the box, generally at 60 the ends of the box, said straps extending about and being aligned with and overlying the cleats, and being located between the outer paper layer and the layer of veneer, and extending continuously around the corner bends of the panels, metal fastening means extending through the straps and the shell and into the cleats, said fastening means being thereby adapted, with the straps, to hold the box structure thus formed firmly together, and end members closing the ends of the space surrounded by the panels.

2. The structure of claim 1 characterized in that the veneer of the panels is separated along the grain into a plurality of closely adjacent but separated wood elements, located in their original position in the veneer, with a separation between adjacent elements of a small fraction of the width of the individual elements, but with the elements sufficiently separated to take up the expansion of the individual elements due to moisture, and thus to prevent cumulative expansion or buckling of the panels by moisture.

3. The structure of claim 1 characterized in that the

flexible metal reinforcing strap is recessed into the exterior surface of the veneer.

4. The structure of claim 1 characterized in that the composite box board shell includes five connecting panels arranged in series, with one end panel of the series adapted to overlap the opposite end panel when the box is fully closed.

5. The structure of claim 1 characterized in that the composite box board shell includes five connecting panels arranged in series, with one end panel of the series adapted to overlap the opposite end panel when the box is fully closed, the metal reinforcing straps extending through all five panels, and overlapping at their ends when the end panels are overlapped, and box locking means positioned to extend through said overlapping panels and into the cleats of the innermost of the overlapping panels.

6. The structure of claim 1 characterized in that the veneer of the panels is separated along the grain into a plurality of closely adjacent but separated wood elements, located in their original position in the veneer, with a separation between adjacent elements of a small fraction of the width of the individual elements, with the elements sufficiently separated to take up the expansion of the individual elements due to moisture, and thus to prevent cumulative expansion or buckling of the panels by moisture, the composite box board shell including five connecting panels arranged in series, with one end panel of the series overlapping the opposite end panel when the box is fully closed, the metal reinforcing straps extending continuously through the five panels.

7. A shipping container consisting of a foldable blank constituting at least three connecting wall panels of a box, the blank consisting of a layer of wood veneer bonded between layers of strong paper, the blank being divided by hingeable portions into a plurality of stiff wall panels located at right angles to each other when the container is assembled for use, each said wall panel having at its ends cleats at right angles to the grain of the veneer,

the cleats being formed and adapted to engage when the panels are bent at right angles to each other, the edges of the adjacent panels being separated by gaps in the veneer having a width not less than the thickness of the veneer, at least one paper layer spanning each such gap, and continuous flexible metal reinforcing straps generally at the ends of the box, said straps extending about and overlying the cleats, and being recessed into the exterior surface of the veneer, and being located between the outer paper layer and the layer of veneer, and extending continuously around the corner bends of the panels, metal fastening means extending through the straps and the veneer and into the cleats, said fastening means being thereby adapted, with the straps, to hold the box structure thus formed firmly together, and end members closing the ends of the space surrounded by the panels.
